VACUUM CLEANER

Robert Lay Hallock, Larchmont, N. Y.

Application June 24, 1942, Serial No. 448,191

2 Claims. (Cl. 15—158)

This invention relates to vacuum cleaner nozzles. It is particularly adapted for use in connection with vacuum cleaners of the pull-tank type, although it is also useful in connection with vacuum cleaners of other types. In a vacuum cleaner of the pull-tank type, a motor, fan, dust bag and filter are mounted in a tank and a suction cleaning tool is connected thereto by means of a long flexible tube or hose. In use, the tank is pulled about by the hose when it is desired to clean in different areas.

The principal object of the invention is to do away with the necessity for the operator of the cleaner carrying about with him a set of tools for cleaning different objects. By using the invention, the operator can clean all types of surfaces without having to put down the hose to obtain a different cleaning tool from a tool box.

Another object of the invention is to provide a suction cleaning tool having two or more cleaning nozzles, any one of which may be attached to the vacuum cleaner hose while another is in use.

Still another object of the invention is to provide a multi-nozzle cleaning tool which may also be used as an elbow for connecting the vacuum cleaner hose to a long wand or tube such as is used in cleaning the rug or floor of a room.

A further object of the invention is to construct a cleaning tool which may also be used as a tube or wand section.

Other objects of the invention will appear as the description thereof is set forth below.

Referring to the drawings forming part of this specification, Fig. 1 is a side elevation showing the general assembly of parts when the invention is in use and the vacuum cleaner is set up for cleaning a rug or floor. Fig. 2 is a side view on a somewhat larger scale, showing the connection of the vacuum cleaner hose to the tool where the upholstery nozzle is in use. Fig. 3 is a side view, partly in section, showing the tool when used as an elbow to connect the hose to the wand in the manner shown in Fig. 1. Fig. 4 is a top view of the tool. Fig. 5 is a view of one end of the tool, showing the plan of the upholstery nozzle, and Fig. 6 is a sectional side elevation showing particularly the construction of the dusting brush end of the tool.

In Fig. 1 there is shown a vacuum cleaner tank 1 to which are connected a flexible hose 2, the tool 3 embodying the present invention, a wand 4 and a suction nozzle 5. Fig. 2 shows the manner of inserting the tube 7 rotatably attached to the hose 2 into the dusting brush end of the

5 combination tool. As shown best in Fig. 3, the tube 7 may be slightly tapered, corresponding to a similar taper on the inside of the combination tool so that they may be pushed together into a nearly air-tight connection. There may be a similar taper on the end of the wand 4, corresponding to the taper on the inside of the dusting brush end of the combination tool 3 so that these parts may likewise be pushed into sealing engagement with one another. Preferably the tapers on all of these parts are the same so that the position of the combination tool may be changed without spoiling the efficiency of the connection. Although in the illustrated embodiment a taper fit is shown, any other means of interconnecting the parts may be used. For example, the tubes might be perfectly cylindrical so as to telescope within one another and means might be provided for locking the parts in engagement. It is, of course, unnecessary that a perfectly air-tight junction be made.

15 The particular form of the suction nozzles formed on the ends of the combination tool may be varied as desired. In the particular embodiment shown, one end of the tool is formed as an upholstery nozzle as shown in Fig. 5. The end of the tube forming the body of the tool is flared outwardly to provide a long lip 8 so that a wide area may be covered when this cleaning tool is in use. To prevent light fabrics from being drawn into the end of the nozzle, the gliders 9 are provided.

20 As shown in Fig. 6, the other end of the tool may be provided with a dusting brush comprising a bristle ring supported in the cup shaped flared end of the tool. A resilient member 11 made of rubber or other suitable material is provided within the bristle ring to prevent the bristles from being forced into the end of the 25 tool when a tube is inserted therein. The member 11 is preferably flexible so as not to interfere with the bristles 10 and to facilitate insertion of the tube. As shown, the member 11 may be continued to form in a single piece a seal 12 30 between the bristle ring and the tube and also a bumper 13.

35 When it is desired to clean a floor or wall or other area considerably removed from the hands of the operator, the vacuum cleaner parts are assembled as shown in Fig. 1. The tool 3 which is bent to form an elbow pipe makes a convenient handle for the operator to grasp when pushing the suction nozzle 5. The suction nozzle 5 may be of the duplex type so that it can be used 40 on a variety of surfaces. When it is desired to

clean upholstery or to dust the top of a table or to clean a curtain or other surface near the hands of the operator, the wand 4 is removed from the tool 3 which may then be used itself as a suction cleaning nozzle. Either end of the tool may be connected to the hose tube and the other end used for cleaning purposes. If it is desired to use the particular suction nozzles on the ends of the tool 3 and it is desired to clean a surface remote from the hands of the operator, the tube 4 may be connected to the hose 2 and the tool 3 connected to the other end of the wand 4. Thus it is seen that an operator using the improved cleaning tool need carry no accessory parts about with him for all parts which he may need are always in use. It is merely necessary for him to rearrange the parts in order to adapt them to his particular need.

While only one embodiment of my invention has been illustrated and described, it is obvious that many changes and modifications therein may be made. For example, if it is desired to use the tool merely as a combination nozzle without serving also as an elbow, the tool may be made with a straight tube instead of bent, as illustrated, and the tube may, if desired, be shortened or even completely eliminated except for the part forming part of the nozzles. If it is desired merely to use the tool as a combination nozzle and elbow, the cleaning nozzle on one end may be omitted. Also, if desired, the tool as thus modified could be made integral with the tube 7 and thus permanently affixed to the end of the hose 6.

It is intended that these Letters Patent shall cover all forms of the invention falling within the scope of the appended claims.

I claim:

1. A combination tool for use with a vacuum cleaner comprising a substantially rigid tube section having straight portions each disposed at an angle to the other and each provided at its free end with a cleaning nozzle, each cleaning nozzle having different cleaning characteristics from the other, the straight portion of each tube section with its respective nozzle being constructed to telescopically receive and frictionally retain another connecting tube section, said combination tool serving as a handle by means of which the connecting tube section may be held or moved, and serving as a joining member between said connecting tube section and a tube leading to a source of suction, or usable separately as a nozzle with either end presentable to work to be cleaned.
2. A combination tool for use primarily with other tubing of a vacuum cleaner and comprising a rigid tube section having two straight end portions disposed at an angle to each other, one provided with a surface cleaner nozzle including a brush having means for holding the bristles out of the way, said end portion with its brush being constructed to telescopically freely receive and frictionally retain a connecting tube section, and the other straight end portion being provided with a surface cleaning nozzle of different cleaning characteristics and also constructed to telescopically receive and frictionally retain a connecting tube section, said combination tool being usable as a joining member between connecting tube sections or separately as a nozzle with either end presentable to work to be cleaned and said combination tube section also serving as a handle by means of which the tubing may be held or moved.

ROBERT LAY HALLOCK.
